UNITED STATES PATENT OFFICE

ROBERT A. DENNISON, OF DALLAS, TEXAS

TOP-SECURING MEANS FOR BASKETS

Application filed December 5, 1927. Serial No. 237,693.

This invention relates to fruit and produce baskets, and more especially to an improved means for securing the top upon the basket, and the principal object resides in the provision of an improved fastening means combining the handle of the basket, in which the handle is so constructed as to be capable of confining the strip overreaching the sides of the top, usually present in the conventional basket construction, while portions thereof are arranged to be bent about or over the hoop to which the slats of the top are secured, consequently firmly binding the top to the basket proper, and positively preventing spreading of the sides of the basket when under strain of a load.

Another object of the invention resides in the provision of a combined handle and top fastening means of the character above specified of an extremely simple and economical construction, and designed to meet all the requirements in the use of this type of basket.

With the foregoing objects as paramount, the invention has particular reference to its salient features of construction and relationship to the basket and top whereby is obtained the secure locking of these parts, and which will be more fully disclosed as the description proceeds.

Figure 1 is a perspective view of a conventional produce basket upon which the improved handle locking means is applied.

Figure 2 is a side elevational view in cross-section, also showing the invention operatively applied.

Figure 3 is a fragmentary exterior view of the basket and top showing the invention applied, the dotted lines indicating the position of the invention previous to clamping, and

Figure 4 is a fragmentary interior view of the basket, showing the invention operatively applied.

In continuing in more detail, it may be stated that baskets 1 to which the present invention especially appertains, are generally constructed of thin strips of tough, bendable wood, and the top 2, being similarly constructed, has a main strip 3 which extends diametrically across the top and overreaches

the sides of the basket. The strips of which the top is composed are affixed to a hoop 4, which, due to the strain the latter is required to withstand, is composed of very strong and durable material. The protruding ends of the main strip 3 are adapted to enter under the bight portion of the handle, which in ordinary baskets, forms the only securing means for the top, and is not at all effective when the basket is overly loaded which is frequently done.

The improvement therefore in the present invention lies in the provision of a handle 5, of strong but bendable wire, substantially U shaped, the legs 6 of which enter the top hoop 7 of the basket 1 and are bent upward. The legs are of such length as to extend to a point equal with or above the bight portion of the handle, as particularly shown by dotted lines in Figure 3. By thus lengthening the legs 6, it is possible, when the top of the basket is in place, to bend the protruding ends of the legs over the edge of the top hoop 4, which firmly binds the top to the basket.

In cases where the basket is overloaded, the flexibility of the sides causes the basket to yield to the pressure of the contents, and as a consequence, the top will not fit. To overcome this condition, the protruding ends of the top strip 3 are inserted into the handles 5 in the usual way, and as shown in Figure 1. Pressure upon the sides of the basket at points adjacent the handles 5 will bring the top hoop 7 of the basket into line with the hoop 4 of the basket top, whereupon the legs 6 of the handle are bent firmly over the hoop 4 of the top, securely binding the top in place.

It is possible that the holes in the hoop 7 of the basket through which the legs 6 of the handle pass, be of such size as to permit the legs to be pulled through, to bring the bight portion of the handle down snugly against the protruding ends of the strip 3, before bending the ends of the legs 6 in place over the hoop 4 of the top, as in Figure 4. While this is not necessary to obtain maximum effect, it strengthens to some degree the binding action already obtained as aforesaid, and enables the protruding ends of the slat 3 to

be used as handles without fear of breaking the latter.

In many types of fastening means designed to hold the top intact upon the basket, 5 the slat 3 is used as a mounting, and co-operates with the handle of the basket. In this form of securing means, the top hoop 4, being subjected to the strain without re-inforcement often becomes released from the slats 10 and weakens the binding effect of the fastening means. Moreover, the slat 3, being of very thin material is easily split, which lends 15 to the insecurity to such a fastening means where the latter is entirely dependent upon the slat for its mounting. The present invention not only is applied to the elements having the greatest strength in the basket construction, namely, the hoops 4 and 7, but reinforces rather than weakens the elements.

20 It will be noted that the legs 6 extend upwardly in divergent relation on the inner faces of the hoops 4 and 7 and across the confronting edges of said hoops while their free ends are bent over and tightly against the 25 top edge of hoop 4 and extend downwardly in divergent relation in engagement with the outer face of hoop 4. This structure not only strengthens and braces the hoops, but also distributes the strain on lifting of the basket, 30 such lifting strain tending to cause the legs to approach each other and thereby increase the holding action thereof.

It may be readily seen that the original 35 form of the fastening arrangement embodying the invention is that illustrated in dotted lines in Figure 3, when the top is placed upon the basket. The most effective tools by which the legs 6 of the handle may be operatively bent over the hoop 4 to bind the top in place 40 have been found to consist of pliers or similar tools, since they are required to be secured simultaneously with an inward pressure upon the side of the basket to aline the hoops 4 and 7, against the resistance of the 45 contents of the basket.

Obviously, the foregoing description has been limited to details, but it should be understood that the invention is not intended to be so limited, and that certain modifications 50 may be resorted to from time to time as considered in keeping with the appended claim, without departing from the spirit of the invention.

I claim:

55 A holder and handle for baskets having top hoops, covers provided with hoops and also with strips which latter extend beyond the cover edges, composed of a substantially inverted U-shaped member formed to receive 60 the strip ends between its legs and to have its horizontal part seat on and against the upper face of the strip, the legs of the member engaging against the periphery of the cover hoop and against the periphery of the top 65 hoop of the basket and being extended

through the said top hoop, the legs having portions extending upwardly at an angle to said legs and in divergent relation across the said confronting edges of the hoops and tightly against the inner face of each hoop 70 and having their free ends bent over and tightly against the top edge of the cover hoop so as to hold the two hoops in tight engagement with each other and extending downwardly in divergent relation in engagement 75 with the outer face of the cover hoop.

In testimony whereof I affix my signature.

ROBERT A. DENNISON.
